US00D755163S

(12) **United States Design Patent**
Yokoyama et al.

(10) **Patent No.:** **US D755,163 S**
(45) **Date of Patent:** **** May 3, 2016**

(54) **ANTENNA**

(71) Applicant: **Murata Manufacturing Co., Ltd.**,
Nagaokakyo-shi, Kyoto-fu (JP)

(72) Inventors: **Tomoya Yokoyama**, Nagaokakyo (JP);
Nobuyuki Tenno, Nagaokakyo (JP)

(73) Assignee: **Murata Manufacturing Co., Ltd.**,
Kyoto (JP)

(**) Term: **14 Years**

(21) Appl. No.: **29/484,789**

(22) Filed: **Mar. 13, 2014**

(51) LOC (10) Cl. **14-03**

(52) U.S. Cl.

USPC **D14/230**

(57) **CLAIM**

The ornamental design for an antenna, as shown and described.

DESCRIPTION

FIG. 1 is a front view of an antenna showing our new design;
FIG. 2 is a rear view thereof;

FIG. 3 is a top plan view thereof;

FIG. 4 is a bottom plan view thereof;

FIG. 5 is a right side view thereof;

FIG. 6 is a left side view thereof; and,

FIG. 7 is a perspective view thereof.

Broken lines in the drawing views are included to show unclaimed subject matter only and form no part of the claimed design.

1 Claim, 2 Drawing Sheets
